UNITED STATES PATENT OFFICE.

WALTER F. KOKEN, OF ST. LOUIS, MISSOURI.

RECLINING-BAR CLAMP FOR BARBERS' CHAIRS.

1,425,325.

Specification of Letters Patent. Patented Aug. 8, 1922.

Application filed December 13, 1920. Serial No. 430,389.

To all whom it may concern:

Be it known that I, WALTER F. KOKEN, a citizen of the United States, residing at St. Louis, Missouri, have invented a certain new and useful Improvement in Reclining-Bar Clamps for Barbers' Chairs, of which the following is a full, clear, and exact description, such as will enable others skilled in the art to which it appertains to make and use the same.

This invention relates to reclining bar clamps for barber chairs.

The object of my invention is to provide a barber's chair or the like which is equipped with an electrically-operated device for releasing the clamp that locks the reclining bar which holds the back and apron of the chair in adjusted position.

Figure 1 of the drawings is a side elevational view of a barber's chair equipped with a reclining bar clamp constructed in accordance with my invention.

Figure 2 is a diagrammatic view, illustrating the wiring of the electrically-operated device for releasing the reclining bar clamp.

Figure 3 is a vertical sectional view, taken on the line 3—3 of Figure 1, looking in the direction indicated by the arrows; and

Figure 4 is a vertical sectional view, taken on the line 4—4 of Figure 3, looking in the direction indicated by the arrows.

Referring to the drawings which illustrate the preferred form of my invention, A designates the seat frame of a barber's chair of conventional design, B designates the back, C designates the apron of the chair and D designates the arms of the chair, said back, apron and arms being joined together in such a manner that a change in the position of the back effects a change in the position of the apron and arms. The standard of the chair is provided with a vertically-disposed socket 1 that receives a vertically-adjustable stem 2 which carries the seat frame of the chair. I have not herein illustrated the means that is used for raising and lowering the stem and for locking the stem in adjusted position, as my present invention relates solely to the means that is used for holding the back of the chair and the parts associated with same in adjusted position.

In barbers' chairs and similar chairs the back and the apron are retained in adjusted position by a bar commonly termed a reclin-

ing bar that is normally locked by a clamping device through which the reclining bar passes. In the chair herein illustrated the reclining bar 3 co-operates with a clamp composed of two jaws 4 and 5 that are normally held in snug engagement with the reclining bar by a resilient means and which are adapted to be separated so as to release the reclining bar by means of an electrically-operated device. The reclining bar 3, as herein illustrated, is pivotally connected at its front end to a bracket 3^a on the apron of the chair and the two jaws 4 and 5 that constitute the reclining bar clamp are pivotally connected together and are held pressed tightly against the reclining bar by springs 6 arranged between the jaw 4 and the heads 7 of laterally-projecting studs 8 on the jaw 5 which pass through holes in the jaw 4, as shown in dotted lines in Figure 3.

The jaws of said reclining bar clamp are separated to release the reclining bar 3 by energizing an electrically-operated device so as to cause one of said jaws to move relatively to the other. Various kinds of electrically-operated devices may be used and any suitable means may be employed for effecting the movement of one or the other of the jaws of the reclining bar clamp when said electrically-operated device is energized. In the form of my invention herein shown a solenoid E which is arranged on the inside of the stem 2 of the chair, as shown in Figure 4, is used for rocking a shaft 9 so as to cause the jaw 4 to move away from the jaw 5, and thus release the reclining bar 3. The shaft 9 is arranged horizontally in the stem of the chair, as shown in Figure 3, and is provided at its left hand end with a coarse screw thread 9^a which extends through a threaded hole in the jaw 5 of the reclining bar clamp, the left hand end of said shaft 9 abutting against the inner side of the jaw 4. The core 10 of the solenoid is connected by means of a link 10^a with an arm 11 on the shaft 9 so as to rock the shaft 9 in one direction, and a spring 12 is connected to said arm 11 so as to rock the shaft 9 in the opposite direction back to its normal position. Normally, the spring 12 holds the shaft 9 in such a position that the jaws 4 and 5 will clamp the reclining bar and thus hold the back and apron of the chair in adjusted position. When the solenoid E is energized by closing the circuit X, the link 10^a

pulls the arm 11 downwardly, thus causing the shaft 9 to move longitudinally of its bearings (to the left, looking at Figure 3), due, of course, to the fact that said shaft is provided with the screw thread 9^a which co-operates with an internal screw thread in the jaw 5. The pressure that said shaft 9 exerts on the jaw 4 moves said jaw away from the jaw 5 sufficiently 10 to release the reclining bar 3, and thus permit the back of the chair to be moved. Thereafter, when the circuit X is opened, the spring 12 restores the shaft 9 to its normal position and the springs 6 force 15 the jaw 4 towards the jaw 5, thus causing the reclining bar to be clamped securely enough to hold the back and the associated parts of the chair in adjusted position.

While I have herein illustrated my invention embodied in a reclining bar clamp composed of two pivotally connected spring-pressed jaws that are adapted to be separated to release the reclining bar by energizing a solenoid whose core actuates a 20 means which effects a change in the relative position of said jaws, I wish it to be understood that the particular form of 25 the reclining bar clamp is immaterial and

that various forms of electrically-operated devices may be used for rendering the reclining bar clamp inoperative without departing from the spirit of my invention. 30

Having thus described my invention, what I claim as new and desire to secure by Letters Patent is: 35

A barber's chair or the like provided with a stem, an adjustable back and an adjustable apron connected so as to move in unison, a reclining bar for controlling the position of said back and apron, a spring pressed 40 clamp for holding said reclining bar in adjusted position, a horizontally-disposed rock shaft journaled in the stem of the chair, co-operating means on said rock shaft and clamp for releasing the clamp when said shaft rocks in one direction, an arm on 45 said rock shaft, a spring that co-operates with said arm to normally hold said rock shaft in a position wherein it has no effect on said clamp, and an electro magnet arranged inside of the stem of the chair and 50 operatively connected with the arm on said rock shaft for moving said shaft in a direction to cause it to release the reclining bar clamp.

WALTER F. KOKEN.
